Specification for Design.

Patented Sept. 16, 1919.

Application filed April 21, 1919. Serial No. 291,764. Term of patent 7 years.

To all whom it may concern:

Be it known that I, WILLIAM FAERBER, a citizen of the United States, residing at Chicago, in the county of Cook and State of Illinois, have invented a new, original, and ornamental Design for a Shampooing Apparatus, of which the following is a specification, reference being had to the accompanying drawing, forming a part thereof.

The figure is a perspective view of this shampooing apparatus, showing my new design.

I claim:

The ornamental design for a shampooing apparatus, as shown.

In testimony that I claim the foregoing as my invention, I have hereunto set my hand.

WILLIAM FAERBER.
